UNITED STATES PATENT OFFICE.

LEWIS EDWARDS, OF NORWICH, CONNECTICUT.

MODE OF SUPPLYING INK TO THE PENS OF PAPER-RULING MACHINES.

Specification of Letters Patent No. 1,309, dated August 31, 1839.

To all whom it may concern:

Be it known that I, LEWIS EDWARDS, of 5
Norwich, in the county of New London and
State of Connecticut, have invented a new
and useful Improvement in Supplying Ink
to the Pens of Common Ruling-Machines,
which is described as follows, reference be-
ing had to the annexed drawings of the
same, making part of this specification.

10 Figure 1 represents a top view of said
improved part of the paper ruling machine.
Fig. 2 represents a vertical section at the
line $\alpha\alpha$ of Fig. 1.

Similar letters refer to similar parts.

15 The nature of this improvement consists
in a new mode of supplying ink to the pens,
by which mode the constant application of
ink with a brush is obviated, as the pens
supply themselves from a fountain in the
20 following manner: Behind the pens I place
a metallic trough A in which the ink is de-
posited. I lay one side of a cloth B across
the pens C. The other side is placed in the

ink in the trough. By raising or lowering
the trough the discharge of the ink is regu- 25
lated as is wanted. In the large trough A
I place small ones D, which are movable and
are for containing various colored inks.

The kind of pens which I usually employ
are those generally supplied by means of a 30
cloth and brush.

What I claim as my invention and which
I desire to secure by Letters Patent con-
sists in—

The peculiar mode of supplying the pens 35
with ink by the combination of the cloth and
ink trough one side of the cloth being placed
over on the pens and the other immersed in
the ink in the trough as before described
which trough also contains smaller troughs 40
for various colored inks as herein set forth.

LEWIS EDWARDS.
